KNOCKDOWN COLLAPSIBLE WARDROBE

Charles Rosenthal, New York, N. Y.

Application September 22, 1943, Serial No. 503,318

3 Claims. (Cl. 312—144)

This invention relates to wardrobes of the type which are sold and delivered to the purchaser in a knocked down collapsed condition and the invention is particularly directed to improvements therein so as to greatly simplify and facilitate the operations incident to the setting up of the wardrobe.

The great majority of wardrobes of this type have presented a serious problem to all concerned due to the difficulties and complications met with on part of the average purchaser when he attempts to set up the wardrobe. In order to overcome these difficulties and objections, the instant invention broadly comprehends an improved wardrobe of the type set forth wherein the units which constitute the top and bottom sections are readily and initially connected to each other in spaced superposed relation by upright spacing strip units after which a plurality of foldable or collapsible body units may be easily applied thereto so that the setting up operation may be accomplished with the greatest facility and without the difficulty and complications usually encountered.

An important object of the invention resides in the production of an improved wardrobe of the indicated character wherein the body forming units which are preferably fashioned of corrugated paper or fiber board, may be more economically produced than heretofore due to the fact that they require only straight or square cuts and scoring and in the less expensive types of wardrobes they are merely bound by adhesive tape applied to the marginal edges thereof.

As a further feature, the invention contemplates the provision of a shelf together with means for supporting the same by the spacing strip units independently of and without imposing any of the supporting strains or stresses upon the body units.

With the above enumerated and other objects in view, the invention is set forth in greater detail in the following specification, particularly pointed out in the appended claims and illustrated in the accompanying drawings, in which:

Fig. 1 is a front view of a wardrobe constructed in accordance with the present invention and illustrating the same in set up condition.

Fig. 2 is a vertical sectional view therethrough taken approximately on the line 2—2 of Fig. 1.

Fig. 3 is a horizontal sectional view of the same taken on the line 3—3 of Fig. 1.

Fig. 4 is a collective perspective view of the wardrobe with the units thereof in separated juxtaposition.

Fig. 5 is a perspective view of the shelf unit separated from the wardrobe.

Referring to the drawings by characters of reference the wardrobe includes top and bottom units A and B, front and rear spacing strip units C and D, a pair of body units E and F and a shelf unit G.

The top and bottom units A and B are of identical construction and each provides a wall 10 having a marginal edge 11 which is rabbeted to provide a reduced inwardly offset inner portion 12 defining a shoulder 13 intermediate the thickness or height of the marginal edge 11. As shown, the wall 10 is preferably in the form of a panel of fiber or paper board, corrugated paper or the like which is carried and enclosed by a marginal frame 14 of wood defining the said marginal edge 11.

The front and rear spacing strip units C and D which are of identical construction, are each preferably fashioned from a length or strip of wood 15 which is longitudinally rabbeted as at 16 at the juncture of the outer face and side edges so that the strip is of cross sectional T-shape configuration, with the rabbeted portion thereof corresponding in size to the size of the rabbeted or reduced inwardly offset portion 12 of the top and bottom units. The inner sides of the strips 15 at the upper and lower ends are cut away to provide upwardly and downwardly projecting tongues 17 and 18 which are of a thickness and length corresponding to the thickness and height of the rabbeted or reduced inwardly offset inner portions of the top and bottom units. This also provides shoulders 19 and 20 which engage with the inwardly disposed surfaces of the top and bottom units A and B to vertically space the same in superposed relation when the top and bottom units are assembled in set up relation with the spacing strip units C and D.

Any suitable means may be provided for connecting and retaining the top, bottom and spacing strip units in assembled set up condition but, as shown, said means consists of cam actuated latch elements 25 carried by the strip units and keeper elements 26 carried by the top and bottom units.

The body units E and F are also of identical construction and the same are each fashioned from a rectangular sheet of any suitable material such as corrugated fiber or paper board stock which is provided with score lines 30 and 31 to provide hingedly connected panels 32, 33 and 34 which permits folding of the units to a compact collapsed arrangement for storage and shipment. The marginal edges of the body units may be

suitably reinforced and protected in any desired manner but as herein illustrated said edges are bound by an adhesive tape 35. The width of the side panels 34 corresponds approximately to the length of the side edges of the reduced inwardly offset inner portions 12 of the top and bottom units A and B, while the width of the front and rear panels 32 and 33 of said body units E and F respectively corresponds to the length of the front and rear edges of the reduced inwardly offset inner portions 12 of said top and bottom units from their juncture with side edges thereof to the side edges of the tongues 17 and 18.

Any desired form of means may be utilized to secure and retain the body units E and F in assembled relation with the top and bottom units A and B so that the upper and lower edges of the rear and side panels 33 and 34 of the body units are disposed between the shoulders 13 of the top and bottom units, with the upper and lower end portions of said panels impinged against the reduced inwardly offset inner portions of the marginal edges 11. The means shown consists of a plurality of turn buttons 38 pivotally mounted on the marginal rear and side edges 11 of the top and bottom units which may be readily swung from their active positions shown in Figs. 1, 2 and 3 where they extend into overlying relation with the upper and lower end portions of the panels 33 and 34 to the inactive out-of-the-way position shown in Fig. 4.

The front panels 32 of the body units E and F serve as doors or closure members for the front of the wardrobe and are preferably provided with knobs 39 for facilitating the opening and closing of the same. Any suitable retaining means such as the turn buttons 40 pivotally mounted on the front spacing strip unit C may be employed for releasably holding the front panels 32 in closed relation with the wardrobe where the free marginal edge portions fit within the rabbeted edge portions of the top and bottom units and the spacing strip unit C. Similar turn button elements 41 pivotally mounted on the rear spacing strip unit D are utilized for assisting in retaining the vertical free edges of the rear panels 33 against said unit.

The shelf unit G which is designed for optional use with the wardrobe consists of a wooden frame 45 enclosing a panel 46. The lower edge of the frame at the front and rear is formed with notches 47 and the portions of the frame at said notches are adapted to be engaged within the clips 48 carried by the inner faces of the spacing strip units C and D. A garment hanger supporting bar 50 is also provided which has secured to the opposite ends thereof the arms 51 for suspending the bar from the shelf by the engagement of the key hole slots 52 in said arms over headed studs 53 projecting inwardly from the opposite end rails of the frame 45. If the shelf unit G is not used, the hanger supporting bar 50 may be supported directly by the wardrobe by engaging the key hole slots of the arms 51 over the headed studs 54 provided for the purpose and projecting inwardly from the opposite side rails of the frame 14 of the top unit A.

In setting up the wardrobe, the bottom unit B is placed on the floor with the reduced inwardly offset inner portion 12 disposed upwardly and the spacing strip units C and D are placed thereon in an upright position and then assembled therewith by fitting the same in place and securing them by the latch and keeper means 25 and 26. If the shelf unit G is to be used it is assem-

bled with the spacing strip units C and D by placing said shelf unit therebetween and engaging the portions of the frame adjacent the notches 47 with the clips 48. The top unit A is next assembled with the spacing strip units C and D by fitting said top unit on the upper ends of the strip units and fastening the latch and keeper means 25 and 26. The body units E and F are then assembled by placing the side panels 34 against the sides of the top and bottom frames 14 to lie against the reduced inwardly offset inner portions 12 of the marginal edges 11 thereof so that the panels 34 lie between the shoulders 13 and the turn buttons 38 are then swung to positions where they overlie the upper and lower edge portions of the panels 34. The rear panels are similarly positioned against the frames 14 and are secured and retained in place by the turn buttons 38 and 41. The front panels 32 of the body units E and F are left free to swing to and from their open and closed relation to the wardrobe so as to serve as doors and are adapted to be releasably retained in closed position by the turn buttons 40.

From the foregoing it will thus be seen that a portable knock-down collapsible wardrobe has been devised which may be readily set up by anyone without difficulty or the complications usually met with in wardrobes of these types now in general use.

What is claimed is:

1. In a knock-down collapsible wardrobe, top and bottom units having rabbeted outer marginal edges defining shoulders intermediate the width thereof, spacing strip units having corresponding rabbeted outer side edges with the opposite ends thereof cut away to provide reduced outer terminals fitted within the rabbeted marginal edges of the top and bottom units and defining inner shoulders engageable with the confronting inner faces of said top and bottom units, means for detachably connecting said spacing strip units to the top and bottom units so as to dispose the rabbeted portions of said units in mating relation, body units having hingedly connected panels fitted within said mating rabbeted portions, a shelf unit, clip elements secured to the inner faces of the spacing strip units adapted to engage over opposite edges of the shelf unit, and means for releasably retaining the body units within the rabbeted portions of the spacing strips and the top and bottom units.

2. In a knock-down collapsible wardrobe, top and bottom units each having marginal edges formed with inwardly offset portions defining a continuous shoulder, a pair of spacing strip units at opposite sides of and between the top and bottom units and supporting the top unit on the bottom unit, detachable means for connecting at least one of the spacing strip units at the opposite ends thereof respectively to the top and bottom units, and a pair of body units each including hingedly connected front, rear and side panels positioned with reference to the assembled top, bottom and spacing strip units so that the body units are disposed between the shoulders of the top and bottom units and the upper and lower end portions of the body unit panels lie against the inwardly offset portions of the top and bottom units, means pivotally carried by the outwardly disposed portions of the marginal edges of the top and bottom units adapted to be swung to positions overlying the end portions of the panels for retaining the body units in assembled relation to the set up top, bottom and spacing strip units, and means releasably retaining the

front and rear panels of the body units inwardly against the spacing strip units.

3. In a knock-down collapsible wardrobe, top and bottom units having rabbeted outer marginal edges defining shoulders intermediate the width thereof, spacing strip units having corresponding rabbeted outer side edges with the opposite ends thereof cut away to provide reduced outer terminals fitted within the rabbeted marginal edges of the top and bottom units and defining inner shoulders engageable with the confronting inner faces of said top and bottom units, means for detachably connecting said spacing strip units

to the top and bottom units so as to dispose the rabbeted portions of said units in mating relation, body units having hingedly connected panels fitted within said mating rabbeted portions, a shelf unit, 5 means provided on the spacing strip units engaging with opposite side edge portions of the shelf unit for supporting the same in a horizontal position therebetween, and means for releaseably retaining the body units within the rabbeted portions of the spacing strips and the top and bottom units.

CHARLES ROSENTHAL.
